OTHER PUBLICATIONS

Gatorade 20 oz. sport bottle; Author: Stokely–Van Camp, Inc.; Date: Mar. 13, 1992.

Primary Examiner—Terry A. Wallace

(74) Attorney, Agent, or Firm—Lars S. Johnson

CLAIM

The ornamental design for a bottle, as shown and described.

DESCRIPTION

FIG. 1 is a perspective view of a bottle showing a new design;

FIG. 2 is a front elevational view of the bottle depicted in FIG. 1, the opposite rear elevational view being identical; FIG. 3 is a side elevational view of the bottle depicted in FIG. 2, the opposite side elevational view being identical; FIG. 4 is a top plan view of the bottle depicted in FIG. 2; and, FIG. 5 is a bottom plan view of the bottle depicted in FIG. 2.

The broken line environmental showing is for illustrative purposes only and does not form part of the claimed design.
